UNITED STATES PATENT OFFICE.

RICHARD K. HOHMANN, OF PERU, INDIANA, AND DAVID BESWICK, OF BROOKLYN, NEW YORK; SAID HOHMANN ASSIGNOR OF HIS ENTIRE RIGHT TO HOHMANN SEWING MACHINE COMPANY, OF PERU, INDIANA, A CORPORATION OF INDIANA, AND SAID BESWICK ASSIGNOR OF HIS ENTIRE RIGHT TO FREDERICK OSANN COMPANY, OF NEW YORK, N. Y., A CORPORATION OF NEW YORK.

VENTILATED ROTARY-HOOK MECHANISM.

Application filed September 22, 1924. Serial No. 739,022.

The object of the present invention is to provide the rotary stitch forming mechanism of a rotary hook sewing machine mechanism with simple and effective provisions 5 for abstracting heat from the revolving hook member and the non-rotating thread carrier or bobbin housing mounted in the hook, by means of air currents created by the motion of the hook. To this end we construct the 10 rotary hook member with simple and effective provisions whereby it acts as a fan to draw air over its surfaces and those of the carrier to thereby absorb and dissipate the frictional heat developed in operation. 15 Advantageously also, the carrier or bobbin housing is formed with a special ventilating passage. The invention is of particular utility in connection with the high speed big bobbin machines heretofore developed 20 by one of us, to-wit: Richard K. Hohmann, on account of the very high peripheral speed of the surfaces of the hook running in contact with the carrier surfaces.

The various features of novelty which 25 characterize our invention are pointed out with particularity in the claims annexed to and forming a part of this specification; but for a better understanding of the invention, its advantages and specific objects attained 30 with it, reference should be had to the accompanying drawing and descriptive matter in which we have illustrated and described a preferred embodiment of the invention.

Of the drawings:

35 Fig. 1 is a front elevation of the rotary stitch forming mechanism of a rotary hook sewing machine;

Fig. 2 is a section on the line 2—2 of Fig. 1;

40 Fig. 3 is a section on the line 3—3 of Fig. 2;

Fig. 4 is a perspective view of a portion of the rotary hook member; and

45 Fig. 5 is an elevation of another portion of the rotary hook member.

The rotary hook member A illustrated in the drawings comprises a hub portion adapted to be secured on the end of the hook shaft (not shown), and spoke arms A' integrally connecting the hub to a cylindrical rim portion A². A second hook rim part

A³ has a portion fitting over the rim part A² and is secured to the latter as by means of screws B² tapped into the rim part A² and passing through holes A⁴ in the rim part A³. The rim part A³ is provided with an internal projecting rib or flange A⁵ at its front end forming the front wall of a circumferential bearing groove C, the rear wall of which is formed by the front edge of the rim portion A², and the outer wall of which is formed by the body of the rim part A². The rim portion of the hook member is notched to form a loop engaging beak A⁶, and the beak forming notch is spanned by the usual deflector strip D.

The bearing groove C in the hook member receives the bearing rim E' of the non-rotating thread carrier or bobbin housing E. The latter is shown as having the usual provisions E² for holding the thread carrier against rotation with the hook member, and is notched to provide the usual thread engaging hook E³ and opposing shoulder E⁴. The bobbin housing is provided with a central post E⁵ on which is normally secured the sleeve portion F' of a separable bobbin housing part F which is latched in place on the end of the post E⁵ by a latch member G. H represents a thread bobbin journaled on the sleeve F'.

The rotary hook member and bobbin housing, in so far as they have been described above, embody no feature of the present invention, but on the contrary are of the type previously developed by Richard K. Hohmann for use in a high speed big bobbin machine with which the present invention may be employed with especial advantage because of the high peripheral speed of the hook member. In such a machine the diameter of the thread housing bearing rim may well be an inch and a half or so, and the hook member may make eight or nine thousand revolutions per minute. With such relative speed of the contacting surfaces of the bearing rim of the bobbin housing and the walls of the bearing groove of the hook member, considerable frictional heat is developed in the regular operation of the machine particularly when, as we consider preferable, the contacting surfaces are not

lubricated. The heating up of the contacting surfaces is objectionable as it increases the frictional wear, and is further objectionable because it makes the bobbin housing 5 part F too hot for comfortable handling by the operator in effecting bobbin replacements.

To avoid this heating up of the parts, we have provided the mechanism shown with 10 simple and effective ventilating provisions which co-operate to create an air flow over the surfaces of the hook member and housing effectually cooling these parts. These provisions, in the preferred construction illustrated, comprise fan blades I secured to the spider arms A' of the hook member A. These blades may be straight or curved, as shown, to correspond to the contour of the front edges of the arms A' and extend outward a short distance beyond the periphery of the rim portion A² and extend rearward some distance beyond the arms A'. A disc K at the rear of the blades fits snugly about the hub portion of the hook 25 member, and is secured against the rear edges of the fan blades I by rivets M by which the disc K is secured to the arms A'. L represents spacing washers surrounding the rivets M. With this arrangement 30 the disc K forms the rear wall of the fan chamber of a centrifugal fan. The blades I draw air into this fan chamber from the space surrounded by the rim of the hook member A, and this air is discharged at the 35 periphery of the fan chamber.

In addition to the ventilating provisions formed by the fan blades I and associated parts, we advantageously form ports or channels A¹⁰ through the portion of the rim 40 of the hook member A forming the outer wall of the bearing groove C. The walls of the ports A¹⁰ serve as fan vanes to create a flow of air through the bearing groove. The fan action thus provided for might be a centrifugal fan action, but advantageously as 45 shown, the ports are forwardly inclined to obtain an impulse fan action whereby air is drawn into the outer ends of the ports A¹⁰ and is delivered at the inner ends of the 50 ports into the bearing groove C. To augment the impulse fan action, the outer ends of the ports A¹⁰ are enlarged as by countersinking, the enlargements A¹¹ being mainly at the forward sides of the axes of the ports A¹⁰. To further the fan action of the 55 channels or ports A¹⁰, we advantageously form a peripheral groove E⁶ in the bearing rim E' of the bobbin housing member E. The groove E⁶ may well be open at its end adjacent the shoulder E⁴, but will ordinarily be closed at its other end. The groove E⁶ is open to the interior of the hook chamber through the usual thread clearing slots E⁷ formed in the bearing rim. 60

65 With the simple and effective provisions

described air is drawn into the hook member through the ports A¹⁰ into immediate contact with the engaging surfaces of the hook member and bobbin housing. The air circulation thus obtained, is augmented by the action of the fan blades I which continuously withdraw air from the interior of the hook member through the openings between the spider arms A'. The ventilating provisions described have been found effective in 70 practice to prevent overheating of the hook member and carrier, and with these provisions the removable bobbin housing part F does not become too warm to be comfortably handled in extended periods of steady operation, while without such provisions a few minutes operation of the mechanism will heat the bobbin housing so hot as to make it practically impossible for the operator to 75 handle it with bare hands. 80

85 While in accordance with the provisions of the statutes we have illustrated and described the best form of our invention now known to us, it will be apparent to those skilled in the art that changes in the form of apparatus specifically illustrated and described herein may be made without departing from the spirit of our invention as set forth in the appended claims, and that certain features of our invention may sometimes be employed with advantage without a corresponding use of other features. 90

95 Having now described our invention what we claim as new and desire to secure by Letters Patent is:

100 1. In a rotary hook sewing machine mechanism comprising a rotating hook member having a bobbin housing chamber and a non-rotating bobbin housing mounted in said chamber, the improvement which consists in provisions creating a fan action drawing air through said chamber and comprising a fan chamber at the rear of the first mentioned chamber receiving air from the latter and discharging it at the periphery of the fan 105 chamber. 110

115 2. In a rotary hook sewing machine mechanism comprising a rotating hook member having an internal bearing groove and a non-rotating bobbin housing journaled in said groove, the improvement which consists in provisions for creating a fan action forcing air through said groove comprising ports through the peripheral wall of the bearing groove. 120

125 3. In a rotary hook sewing machine mechanism comprising a rotating hook member having an internal bearing groove and a non-rotating bobbin housing journaled in said groove, the improvement which consists in provisions for creating a fan action forcing air through said groove comprising forwardly inclined ports through the peripheral wall of the bearing groove. 130

4. In a rotary hook sewing machine mech-

anism comprising a rotating hook member having an internal bearing groove with ports in the peripheral wall of the groove, and a non-rotating bobbin housing having a bearing rib mounted in said groove and formed with a peripheral channel.

5. In a rotary hook sewing machine mechanism comprising a rotating hook member having an internal bearing groove and a non-rotating bobbin housing mounted there-
10 in, the improvement which consists in for-
wardly inclined ports extending through the peripheral wall of said bearing groove, and provisions incorporated in the hook member

for creating a fan action drawing air out of 15
the hook at the rear of the latter.

6. A rotary hook member for a rotary hook sewing machine comprising hub and rim portions and arms connecting said portions, fan blade ports extending rearwardly 20
from said arms, and a disc surrounding said hub and forming the rear wall of a fan chamber at the rear of said arms.

Signed at Brooklyn, in the county of Kings and State of New York, this 19th day 25
of September, A. D. 1924.

RICHARD K. HOHMANN.
DAVID BESWICK.
